UNITED STATES PATENT OFFICE.

HERMAN VOSS, OF HORICON, WISCONSIN.

WRENCH.

1,281,886.

Specification of Letters Patent. Patented Oct. 15, 1918.

Application filed August 9, 1916. Serial No. 113,981.

To all whom it may concern:

Be it known that I, HERMAN Voss, a citizen of the United States, residing at Horicon, in the county of Dodge and State of Wisconsin, have invented new and useful Improvements in Wrenches, of which the following is a specification.

The present invention relates to pipe and nut wrenches.

10 The object of the invention is to produce a wrench which may be easily and quickly operated to adjust the jaws thereof and which shall be of a simple construction and comparatively cheap to manufacture and operate.

With the above and other objects in view the improvement resides in the construction, combination and arrangement of parts set forth in the following specification and falling

20 within the scope of the appended claim.

In the drawing:

Figure 1 is an elevation of a wrench constructed in accordance with the present invention,

25 Fig. 2 is a sectional view approximately on the line 2—2 of Fig. 1,

Fig. 3 is a sectional view approximately on the line 3—3 of Fig. 2,

30 Fig. 4 is a sectional view approximately on the line 4—4 of Fig. 1, and

Fig. 5 is a perspective view of the frame or carriage.

Referring now to the drawing, the numeral 1 designates the handle of the wrench

35 which has one of its ends rounded from its opposite edges and terminating in the toothed jaw 2. The numeral 3 designates the shank of the movable jaw 4 and the said shank has one of its edges provided

40 with transversely arranged substantially V-shaped teeth 5. The smooth edge of the shank rests upon one of the edges of the handle 1 and overlies the jaw 2 as clearly illustrated in the drawing. The numeral 6

45 designates a frame or carriage that straddles the shank of the jaw 4 and the handle of the jaw 2, the handle 1 being pivotally secured to the said carriage, as at 7, and the carriage at its corner opposite the pivot is

50 formed with a yoke member 8 that is provided upon its inner surface with a longitudinal depression 9 which provides a seat for a flat spring 10 that is secured to the handle 1, as at 11. The outer connecting member for the frame or the member dis-

posed away from the toothed edge of the shank 3 is indicated by the numeral 12 and this member is formed upon its inner surface with a longitudinally disposed depression or channel 13 to receive a convolute 60 spring 14, the opposite ends of said spring bearing against offset members 14' providing finger pieces 15 in dogs 16, the dogs being pivotally secured to the sides of the carriage 6, as at 17. These dogs are normally forced by the spring 13 to engage with the teeth 5 of the shank of the jaw 4. The numeral 18 designates a plate which is arranged between the sides of the carriage 6 and is disposed over the toothed edge 5 of the 70 shank 3. This plate has its opposite ends centrally slotted, as at 19, whereby to receive the engaging ends of the dogs 16.

From the above description, taken in connection with the accompanying drawing, the 75 simplicity of the device, as well as the advantages thereof will, it is thought, be perfectly apparent to those skilled in the art to which such invention appertains without further detailed description.

Having thus described the invention, 80 what I claim is:

A wrench comprising a relatively fixed jaw member, a movable jaw member slidably engaged upon one edge of said relatively fixed member, a substantially inverted U-shaped carriage pivotally connected with said first named jaw member and disposed in straddling relation to both of said jaw members, a yoke formed on said carriage and extending outwardly beyond the outer edge of said first named member, a leaf spring secured to the outer edge of said first named member and bearing against the inner edge of said yoke, a plurality of teeth 90 formed on the outer edge of said second named member, a pair of pawls pivoted within said carriage and having their ends engageable with said teeth, finger engaging portions formed on said pawls and entirely 95 inclosed within said carriage, and a coil spring disposed between said finger engaging portions and urging said pawls into engagement with said teeth, movement of said finger engaging portions toward each 100 other disengaging said pawls from said teeth.

In testimony whereof I affix my signature.

HERMAN VOSS.
